Primary Examiner — Kevin K Rudzinski*Assistant Examiner* — Paul D Bohannon(74) *Attorney, Agent, or Firm* — Schwabe Williamson & Wyatt, PC(57) **CLAIM**

We claim the ornamental design for a park bench, as shown and described.

DESCRIPTION

FIG. 1 is a perspective view of the park bench;

FIG. 2 is a left side view thereof;

FIG. 3 is a front view thereof;

FIG. 4 is a top plan view thereof; and,

FIG. 5 is a bottom view thereof.

The broken lines shown in the drawings are for the purpose of illustrating portions of the article and form no part of the claimed design.
